DISPLAY CABINET

Benjamin M. Levinger, Millbrae, Calif., assignor
to Schlage Lock Company, a corporation

Application May 8, 1951, Serial No. 15,099

Term of patent 14 years

(Cl. D80—11)

To all whom it may concern:

Be it known that I, Benjamin M. Levinger, a citizen of the United States, residing at Millbrae, county of San Mateo, State of California, have invented a new, original, and ornamental Design for a Display Cabinet, of which the following is a specification, reference being had to the accompanying drawing, forming a part thereof.

Figure 1 is a front perspective view of a display cabinet, showing my new design, in an opened position;

Figure 2 is a perspective view, in a closed position; and

Figure 3 is a cross sectional view thereof, taken on the line 3—3 of Figure 1.

I claim:

The ornamental design for a display cabinet, as shown.

BENJAMIN M. LEVINGER.
